(57) **CLAIM**

The ornamental design for a user interface for coffee maker,
as shown and described.

DESCRIPTION

FIG. 1 is a perspective view of the user interface for coffee
maker showing our new design embodiment;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in
FIG. 1;

FIG. 6 is a top view of the embodiment shown in FIG. 1;
FIG. 7 is a bottom view of the embodiment shown in FIG.
1;

FIG. 8 is a perspective view of the user interface for coffee
maker, showing our new design another embodiment;

FIG. 9 is a front view of the embodiment shown in FIG. 8;
FIG. 10 is a rear view of the embodiment shown in FIG. 8;
FIG. 11 is a side view of the embodiment shown in FIG. 8;
FIG. 12 is another side view of the embodiment shown in
FIG. 8;

FIG. 13 is a top view of the embodiment shown in FIG. 8;
and,

FIG. 14 is a bottom view of the embodiment shown in FIG.
8.

The broken lines in the figures are for environmental pur-
poses only and form no part of the claimed design.

1 Claim, 14 Drawing Sheets
